US00D876972S

(12) **United States Design Patent** (10) Patent No.: **US D876,972 S**
(45) Date of Patent: **** Mar. 3, 2020**

(54) **BODY COMPOSITION ANALYZER**

(71) Applicant: **LG ELECTRONICS INC.**, Seoul (KR)

(72) Inventors: **Hyunjin Yoon**, Seoul (KR); **Hophil Lee**, Seoul (KR)

(73) Assignee: **LG ELECTRONICS INC.**, Seoul (KR)

(**) Term: **15 Years**

(21) Appl. No.: **35/506,608**

(22) Filed: **Jul. 27, 2018**

(80) **Hague Agreement Data**

Int. Filing Date: **Jul. 27, 2018**

Int. Reg. No.: **DM/102296**

Int. Reg. Date: **Jul. 27, 2018**

Int. Reg. Pub. Date: **Feb. 1, 2019**

(30) **Foreign Application Priority Data**

Feb. 2, 2018 (KR) 30-2018-0006013

(51) **LOC (12) Cl.** **10-04**

(52) **U.S. Cl.**

USPC **D10/83**

(58) **Field of Classification Search**

USPC D10/91, 92, 83

CPC .. A61B 10/0045; A61B 5/0537; A61B 5/0031
